CRANK PRESS

Karl Götz, Lauter, Germany

Application October 19, 1933, Serial No. 694,319
In Germany October 19, 1932

13 Claims. (Cl. 18—16)

This invention relates to a press in which the crank actuating the press plunger, which shall be referred to as the pressing crank, is not directly connected to the driving machine or to the handle for operation by hand, but an auxiliary crank is interposed in this connection, which on the one hand is turned by the driving machine or the handle, but transmits its motion to the pressing crank only through one or more pull bars, links 5 or the like. In place of the pressing crank or the auxiliary crank or both eccentrics may be employed.

A crank press with two cranks is thus obtained and the motion of the press plunger can in this 15 way be influenced in a variety of ways in spite of the approximately constant motion of the driving machine.

It is the object of this invention to arrange the two cranks so with respect to one another that the 20 velocity of the motion of the press plunger will steadily decrease from the upper dead centre position to the bottom dead centre position and to provide other means which render the press especially adapted to the pressing of plastic materials as artificial resins, insulating materials or 25 the like.

The invention is clearly illustrated in the accompanying drawings, in which:—

Fig. 1 shows diagrammatically the motions in 30 connection with the arrangement of the cranks.

Fig. 2 is a side view of the press,

Fig. 2a is a front view of the press,

Fig. 3 is a longitudinal section of the slip coupling, and

Fig. 4 is a cross section of the slip coupling or clutch.

For this purpose the employment of double cranks provides a particularly great advantage as is illustrated diagrammatically in Figure 1 40 of the accompanying drawing.

In this figure *a* represents the pressing crank, *b* the auxiliary crank, *c* the pull bars connecting the two cranks and *d* the connecting rod leading to the press plunger *e*.

According to the invention the two cranks are 45 so arranged with respect to one another that at the end of the pressure applying stroke of the pressing crank *a*, the pull bars *c* pass approximately through the centre of rotation of the auxiliary crank *b*. From this it will be seen at once that to a great motion of the crank *b* there corresponds at this place a very short motion of the press plunger *e*. Thus considerable power is applied just when the press plunger is in its bottom 50 position and artificial resins can consequently

be pressed particularly effectively. During the upward motion of the plunger the latter lifts correspondingly slowly from the pressing mould, so that the pressed article can be lifted undamaged out of the mould, (Fig. 1 broken lines).

According to the invention the press is furthermore so constructed that during the continuation of its stroke the pressing crank moves very rapidly, so that the idle running period of the press is very short. For this purpose according to the 10 invention the two cranks are so arranged with respect to one another that at the end of the lifting off stroke of the pressing crank *a* the pull bars *e* pass approximately through the centre of rotation of the crank *a*, as is shown in Fig. 1 by full lines. 15

The motions occurring between these two positions are indicated in Fig. 1 by five intermediate positions. It will be seen that with constant distance of travel of the auxiliary crank *b*, the distances of travel of the press plunger are at first 20 very great but become very small in the lower pressing position. By simply measuring the distances it will be seen that to the first sixth—16.6% of the motion of the auxiliary crank *b* there corresponds a motion of 32.3% of the stroke of the 25 press plunger, while to the last sixth of the motion of the auxiliary crank there corresponds only 1.6% of the stroke of the press plunger. Thus a very rapid idle stroke and a very slow highly effective pressing stroke are obtained.

In designing this construction it has been found to be of advantage to give the auxiliary crank *b* the same radius as the pressing crank *a*. From the constructional point of view this results in the simplest conditions, more particularly if the pull 35 bars *c* be made longer than the distance between the centre of rotation of the two cranks.

Fig. 2 shows a constructional form of such an arrangement of a press. On the top of the press frame *m* an electric motor *n* is mounted, which 40 drives through gearing *o* of the auxiliary crank *b*, consisting of a plurality of toothed wheels. For smaller types of presses it is not necessary to provide an electric motor, in this case special means for operation by hand will be sufficient. Especially a handle or a lever arranged on a crank cheek may be used as is shown in Fig. 2 by dotted lines. It is also possible to arrange a wheel provided with handles on the crank shaft.

The auxiliary crank is connected by the pull 50 bars *c* with the pressing crank *a*. On the crank pin of the pressing crank there is also arranged the connecting rod *d* which acts on the press plunger *e*. For the rest the press corresponds to the usual constructional forms.

The constructional form of the press according to Fig. 2 shows an arrangement in which the pull bars *c* act directly on the crank pin of the pressing crank *a*. With this arrangement very favourably loading of the crank *a* is obtained, as it is by this means relieved of any torque. A plurality of connecting rods and a plurality of pull bars *c* may be provided or the pull bars and connecting rods embrace one another in a bifurcated manner. The advantage of the double crank drive may of course also be fully utilized if the drive of the pressing crank be derived in any other way from that of the auxiliary crank.

Furthermore a special slip coupling must be provided in order to prevent overloading of the press on the one hand in cases where too much pressing material is placed under the press plunger and on the other hand, when pressing plastic materials, to keep the pressing pressure constant in the down position of the press plunger for the time during which the plastic materials are flowing into all parts of the mould.

According to the invention this slip coupling is of the hydraulic type, the rotor of same being fixed upon the one part of the shaft and the casing or housing being attached to the other part of the shaft. Between the suction and the pressure chamber of the coupling a bore has been provided in which a throttling or stopping means is arranged allowing the liquid to flow through when the pressure has reached a certain amount. The interior of the casing is fully or partly filled with a liquid as for example oil, the liquid being sucked in by the rotor and being delivered back to the suction chamber by way of the bore. When using oil the rotating parts are lubricated at the same time.

In ordinary working the clutch chiefly acts as a rigid coupling in which case the liquid does not circulate at all. Only when the power to be transmitted has reached a certain amount the stopping means will be opened by the pressure produced and a relative movement of the rotor towards the casing will occur. In this way the pressure will be kept constant without the plunger making any movement. The same result may be obtained when the motion of the press plunger is prevented by some obstacle as for example too much material in the press mould.

Instead of using a stopping means which opens only at a certain amount of pressure of the liquid a jet may be provided which always allows a certain circulation of liquid and which produces a certain throttling effect limiting the power to be transmitted.

For such a hydraulic coupling all known designs of pumps may be used, for example piston pumps, gear pumps, centrifugal pumps and so on. The invention relates to a special type of pumps having a rotor eccentrically arranged in the casing, this rotor having slots in which blades are provided sliding on the inner part of the casing.

Figs. 4 and 3 show such a coupling in longitudinal section and cross section. The casing or housing *f* is fixed upon the shaft *g* and is rotatably mounted on the shaft *h*, being made liquid-tight towards this shaft by means of a packing bush. The rotor *i* is fixed upon the shaft *h*. It consists of a centre part in which slots are provided. In these slots blades are slidably arranged of the same width as the centre part. The blades *l* slide with their outer part on the eccentric part *p* of the casing and are pushed

inward by the relative movement of the rotor against the casing as shown in Fig. 4.

When moving in this way the blades *l* suck liquid from the suction chamber *r* and push it through the bore *s*. In this bore a spring loaded valve *t* is arranged through which, the valve being opened, the fluid may return to the suction chamber *r* by way of the bore *u*. The pressure of the liquid and correspondingly the power to be transmitted may be changed by changing the tension of the spring *w*.

When the coupling rotates the blades are pushed outward by the centrifugal force thereby tightening themselves sufficiently against the eccentric part *p*. To assist the centrifugal force the slots *k* are inter-connected by a groove *v* so that the fluid pushed inward by a blade will push another blade outward.

The opening of the bore *s* must be situated near the end of the pressure chamber so that the liquid can flow out. In order to avoid too high pressure in those sections of the pressure chamber which are not communicated with the bore *s* openings *x* are provided in the blades *l* to allow a back flow of the liquid. These openings *x* are closed by the inward motion of the blades *l* in such a way that the opening of a blade will not be fully closed until the blade ahead in the turning direction has given free the opening to the bore *s*.

The coupling will act as a slip coupling as described above when the direction of rotation corresponds to the arrow *y*. When rotating in the other direction it will chiefly work as a rigid coupling on account of the liquid not being able to leave the pressure chamber.

If it is desired to have the coupling work as a sliding coupling in both directions of rotation another opening similar to the opening of the bore *s* may be provided near the narrowest part 40 of the pumping chamber. This opening would have to lead to another stopping means corresponding to the valve *t*.

The hydraulic coupling has the special advantage that its outside forms a smooth cylinder 45 which may be used as brake disc for brake shoes or brake bands.

Having now particularly described and ascertained the nature of my said invention and in what manner the same is to be performed, I declare that what I claim is:—

1. A press for artificial resins, insulating materials and other plastic materials comprising a frame, a press plunger, a crank drive adapted to move said press plunger, an auxiliary crank, pull bars connecting said auxiliary crank with said crank for the press plunger and means adapted to drive said auxiliary crank by a source of power, the two cranks being so arranged with respect to one another that at the end of the pressure-applying stroke of the pressing crank the pull bars pass approximately through the center of rotation of the auxiliary crank, while at the end of the lifting stroke of the pressing crank the pull bars pass approximately through the center of rotation of the pressing crank.

2. A press as defined in claim 1 characterized by the feature that both cranks have the same radius.

3. A press as defined in claim 1 characterized by the feature that the length of the pull bars is different from the distance between the centres of the cranks.

4. A press for artificial resins, insulating materials and other plastic materials comprising a

- frame, a press plunger, a crank drive adapted to move said press plunger, an auxiliary crank, pull bars, connecting said auxiliary crank with said crank for the press plunger and means adapted to operate said auxiliary crank by hand, the two cranks being so arranged with respect to one another that at the end of the pressure-applying stroke of the pressing crank the pull bars pass approximately through the center of rotation of the auxiliary crank, while at the end of the lifting stroke of the pressing crank the pull bars pass approximately through the center of rotation of the pressing crank. 5
5. A press for artificial resins, insulating materials and other plastic materials comprising a frame, a press plunger, a crank drive adapted to move said press plunger, an auxiliary crank, pull bars connecting said auxiliary crank with said crank for the press plunger, means adapted to drive said auxiliary crank by a source of power, and a hydraulic slip coupling arranged in alignment with the drive means for permitting a constant slipping of long duration whereby the press will remain temporarily under pressure while the drive continues to run. 10
6. A press as defined in claim 5 wherein the slip coupling includes communicating suction and pressure chambers and throttling means arranged between the suction and pressure chamber of the coupling adapted to allow a circulation of the liquid when the power to be transmitted reaches a certain amount. 15
7. A press for artificial resins, insulating materials and other plastic materials comprising a frame, a press plunger, a crank drive adapted to move said press plunger, an auxiliary crank, one or more pull bars, links connecting said auxiliary crank with said crank for the press plunger, means adapted to drive said auxiliary crank by an electric motor, a hydraulic slip coupling which permits a constant slipping of long duration arranged in the shaft line of the driving means and including communicating suction and pressure chambers, throttling means arranged in the coupling between the suction and pressure chamber of same adapted to allow a circulation of the liquid when the power to be transmitted reaches a certain amount, means provided in the coupling adapted to allow a back flow of liquid from sections in communication with the throttling means into the following section of the pressure chamber and a brake composed of brake shoes and a brake disc consisting of the outer part of the coupling which has the form of a cylinder. 20
8. A press for artificial resins, insulating materials and other plastic materials comprising a frame, a press plunger, a crank drive adapted to move said press plunger, an auxiliary crank, pull bars connecting said auxiliary crank with said crank for the press plunger, means adapted to drive said auxiliary crank by a source of power, and a slip coupling which permits a constant slipping of long duration arranged in alignment with the driving means and consisting of a hydraulic coupling including communicating suction and pressure chambers and throttling means arranged between the suction and pressure chamber of the coupling adapted to allow a circulation of the liquid when the power to be transmitted reaches a certain amount, said hydraulic coupling also including a shaft, a rotor arranged concentrically on the shaft, a casing having the inner part arranged eccentrically to the shaft and the rotor including blades which are moved inwardly when the rotor moves relative to the casing. 25
9. A press as claimed in claim 8, wherein the rotor is provided with slots in which the blades slide and are connected by a groove allowing the liquid to flow from one slot to the other. 30
10. A press as claimed in claim 8, wherein the communication between the suction and pressure chambers consists of a bore, and the throttling means includes a spring loaded valve and means for varying the load on the valve. 35
11. A press as claimed in claim 8, wherein the blades are provided with an opening being so arranged on the surface that the openings enter the slot at the same time the blade ahead in the turning direction has passed the communication point between the suction and pressure chamber. 40
12. A press as claimed in claim 8, wherein another opening, similar to the opening of the bore, is provided in the vicinity of the narrowest part of the pumping chamber leading to another stopping means which corresponds to the valve. 45
13. A press as claimed in claim 8, characterized by the feature that instead of a valve one or several jets are provided adapted to allow the circulation of liquid with a resistance according to the power to be transmitted by the coupling. 50

KARL GÖTZ.
